DISPENSER

James H. Wheeler, Milwaukee, Wis.

Application January 17, 1944; Serial No. 518,515

5 Claims. (Cl. 222—226)

This invention relates to improvements in dispensers, and more particularly to a device for delivering a limited or given quantity of a powdered or granulated commodity such as soap.

A general object of the invention is to provide a dispenser for powdered soap or the like which is susceptible of easy attachment to a wall or supporting surface for conveniently delivering batches of material to a user, the dispenser being easy and positive in its operation, susceptible of easy refilling, and providing a compact and attractive container.

A more specific object of the invention is to provide a powdered or granulated material dispenser equipped with a movable batch delivering mechanism having associated therewith a movable agitator to keep the material within the dispenser loose and uncaked for ready delivery through the delivering mechanism and from the dispenser.

A further object of the invention is to provide a dispenser in which the container or housing, as well as the major portions of the agitating and delivery mechanism, may be molded from plastics.

A further object of the invention is to provide a dispenser comprising a minimum number of parts susceptible of easy manufacture and arranged for quick and simple assembly.

A further object of the invention is to provide a dispenser which is of very simple construction, is strong and durable, is neat and attractive in appearance, is economical to use, and is well adapted for the purposes set forth.

With the above and other objects in view the invention consists of the improved dispenser, and its parts and combinations, as set forth in the claims, and all equivalents thereof.

In the accompanying drawing in which the same reference characters indicate the same parts in all of the views:

Fig. 1 is a front view of the improved dispenser;

Fig. 2 is a plan view thereof with a portion of the cover broken away to show structural details of the delivering mechanism and agitator;

Fig. 3 is a transverse, vertical sectional view taken on line 3—3 of Fig. 2;

Fig. 4 is a longitudinal, vertical sectional view taken on line 4—4 of Fig. 3;

Fig. 5 is a detail view of the delivering, grooved shaft and the operating knob thereon; and

Fig. 6 is a detail view of the agitator.

Referring now more particularly to the drawing it will appear that the dispenser includes a

box-like upright container 10 of substantially rectangular form with a curved lower bottom portion 10' providing within the lower portion of the container a curved wall 11 extending away from a hollow, internal boss 12. The open upper end of the container body 10 is closed by a removable cover 13. The meeting edges of the container body and cover have complementary shoulders and recesses, as best shown in Figs. 3 and 4. The back wall of the container body 10 is formed with an internal rib 14 and on opposite sides of the rib are screw apertures 15. The latter are for the purpose of receiving screws by which the container body is affixed to a wall or support in proximity to its point of use. To removably hold the cover 13 on the container body 10 in a manner to prevent its easy or unauthorized removal and also making difficult access to the heads of attaching screws lodged against the apertures 15, a cover bolt 16 is passed through an opening in the rear of the cover and is threaded into a tapped opening 17 in said rib 14. The head of the bolt 16, which is preferably hexagonal, is seated in a recess 18 to prevent removal of the bolt except with a proper tool. The container body and cover are preferably cast from a suitable plastic and exterior portions may be attractively formed and decorated. The exact shape of the container and its proportions is subject to variation, depending on where the device is to be located, the commodity to be dispensed, and other factors.

A material delivering, grooved shaft is designated by the numeral 19 and it is adapted to be inserted through the bore of the container boss 12, said bore being transverse of the container body and having an open end at one side of the container. The outer end of the shaft 19 has an integral hand knob 20 for turning purposes. An intermediate outer surface portion of the shaft 19 is formed with an eccentric groove 21 whose shape is best shown in Fig. 5. The top of the boss 12 is formed by a flat, horizontal shelf 22 which partially overhangs the shaft 19. Said shelf is provided with a longitudinal slot 23 having an enlargement 23' at one end.

Adapted to be reciprocated back and forth within the bottom portion of the container is an agitator 24 which is preferably eccentrically curved to follow the contour of the boss 12 and bottom wall 11. The inner or head end of the agitator blade carries a depending headed stud 25. The shank of the stud 25 is received by the shelf slot 23, while the head of the stud is lodged

within the eccentric groove 21 of the shaft 19.

From the foregoing description the operation of the improved dispenser should be obvious. The user will hold one hand or a container below an outlet opening 26 in the lower portion of the container body 10 and grasp the shaft knob 20 with his other hand, turning the latter in the direction indicated by the arrow in Fig. 3 or rearwardly. This movement will rotate the shaft 19 and cause a turning movement of the eccentric groove 21 relative to the axis of the shaft. The head 25 of the stud of the agitator 24 rides in said groove 21 whereby the agitator is reciprocated back and forth lengthwise of the curved bottom portion of the container body. As the container body is packed or filled with a powdered or granulated commodity such as soap, the movement of the agitator, which occurs every time the shaft is turned for dispensing purposes, keeps the commodity in a free and loose condition and prevents caking.

The turning movement imparted to the shaft 19 is also effective for dispensing or delivering a limited or given quantity of the commodity. Portions of the groove 21 will, of course, register with the cavity of the container body and the powdered commodity will enter into the groove 21. As the shaft is turned, portions of the groove 21 will ultimately register with the discharge opening 26 through which a limited quantity of the commodity will then drop for use. The exact location of the discharge opening 26 is not important other than that it be arranged to register with the shaft groove 21 so that material may gravitate therethrough.

While the dispenser is especially well adapted for handling powdered or granulated soap, it is obvious that it could be used for the dispensing of grains, chemicals and similar products, it being obvious that for some of the latter products the container and delivering mechanism would be substantially larger than if the device were used for dispensing soap.

One of the important features of the invention is the simplicity of the dispenser and the facility with which the same may be assembled. In essence the dispenser comprises but four parts, all of which may be molded from suitable plastics or any other suitable material, said parts comprising: the container body 10, the container cover 13, the integral delivering shaft 19 carrying the knob 20, and the agitator 24. When the device is to be assembled the delivering shaft 19 is inserted through a side of the container body into the recess of the boss 12. The head 25 of the agitator stud is then entered through the shelf slot enlargement 23' and moved along the slot so as to engage the shaft recess 21. The shaft 19 is finally locked in its completely inserted position, and against undesired withdrawal by a peg 27 which is driven through an opening in the bottom portion of the container body and caused to lodge in an annular groove 28 formed in the inner end of the shaft 19. The mounting of the container body on a wall or support was previously described, as was the attachment of the cover 13. It might, additionally, be mentioned that the peg 27 operating in the shaft groove 28 keeps the groove clean and free of undesired material which might lodge therein.

Various eccentric movements of the agitator may obviously be accomplished by irregularities in the shelf slot 23 and depth of the shaft slot 21 whereby, in addition to reciprocations of the

agitator in one direction, it could be caused to oscillate sidewise and also up and down.

From the foregoing description it will appear that the improved dispenser is of very simple and novel construction and is well adapted for the purposes described.

What is claimed as the invention is:

1. A dispenser, comprising a container having a discharge opening in a lower portion thereof, a shaft revolvably mounted in a lower portion of said container and having a portion extending externally of the container for manipulating purposes, a portion of said shaft being formed with a curved groove, adapted, during turning movements of the shaft, to register with the interior of the container and with the discharge opening for delivering batches of material from the former to the latter, and an elongated eccentrically shaped agitator having a blade extending across the bottom of the container and a headed extremity engaging said shaft groove whereby turning movements of the shaft will reciprocate the entire agitator in a substantial path across the interior of the container.

2. A dispenser, comprising a container having a discharge opening in a lower portion thereof, a shaft revolvably mounted in a lower portion of said container and having a portion extending externally of the container for manipulating purposes, said shaft being formed with a curved groove, adapted, during turning movements of the shaft, to register with the interior of the container and with the discharge opening for delivering batches of material from the former to the latter, a slotted shelf overhanging said shaft, and a bodily movable agitator within the container and having a portion extended through and guided by said shelf slot and lodged within said shaft groove whereby turning movements of the shaft will reciprocate the entire agitator in a predetermined path.

3. A dispenser, comprising a container having a discharge opening in a lower portion thereof, a shaft revolvably mounted in a lower portion of said container and having a portion extending externally of the container for manipulating purposes, said shaft being formed with a curved groove, adapted, during turning movements of the shaft, to register with the interior of the container and with the discharge opening for delivering batches of material from the former to the latter, a slotted shelf overhanging said shaft, and an elongated eccentrically shaped agitator having a blade extending across the bottom of the container and having a downturned inner shank extended through and guided by said shelf slot, said shank terminating in a knob engaging said shaft groove whereby turning movements of the shaft will reciprocate the agitator.

4. A dispenser, comprising a container having a discharge opening in a lower portion thereof, a bearing recess within a lower portion of the container, a cylindrical shaft movably engaging said bearing recess and extending exteriorly of the container for manipulating purposes, means for securing the shaft to the container, an intermediate portion of the surface of said shaft being formed with an endless curved groove affording communication between the interior of the container and the discharge opening, and an agitator bodily movably supported within the container and having a portion engaging said shaft groove whereby movements of the shaft reciprocate the

entire agitator across the interior of the container.

5. In a dispenser, a hollow one-piece box-like body open at its upper end and having a relatively thick and upwardly, rearwardly curved, bottom wall formed with a discharge opening therethrough and a recess, a shaft revolubly extended through a side wall of the body into said recess and having an external, integral manipulating knob, a portion of the shaft within the body having an endless, curved material convey-

ing groove affording communication between the interior of the body and said discharge opening, a bodily movable agitator within the body and having a terminal portion seated in said shaft groove whereby, when the shaft is turned, the entire agitator is moved in a substantial path across the interior of the container, a one-piece cover closing the open upper end of the body, and fastening means between the body and cover.

JAMES H. WHEELER.
